ELECTRIC MOTOR

Eldon R. Cunningham, Fort Wayne, Ind., and Earl K. Stewart, Scotia, N.Y., assignors to General Electric Company, a corporation of New York

Filed Dec. 26, 1962, Ser. No. 72,944

Term of patent 14 years

(Cl. D26—5)

Fig.1.

Fig.2.

Fig.3.

FIG. 1 is a perspective view of an electric motor employing the new design;

FIG. 2 is a plan elevational view as seen from the top of FIG. 1; and

FIG. 3 is an end elevational view of reduced size as seen from the bottom of FIG. 1.

The dominant features of the design reside in the portions shown in full lines, and are characterized primarily by a circular motor end frame having a raised section in the axial direction bounded by a pair of generally radial edges to define a raised circumferential length less than 180° with a cover plate overlying a major portion of the raised section. These features are further characterized by an axially raised generally radiating bar projecting diametrically away from each edge in a generally radial direction, terminating adjacent the outer periphery of the frame remote from the raised section. In addition, three arcuate shaped openings are spaced radially inward from the frame periphery, one extending angularly between the sides of the raised bars diametrically opposite to the raised section, the other two respectively projecting from the side of each bar, remote from the other bar, toward

the associated edge of the raised section, with the three openings and two bars together having an angular length greater than 180°. A curved plate is mounted on the end frame, adjacent one of the edges of the raised section, radially between one of the arcuate shaped openings and the outer frame periphery. These features and shapes are all shown by the full lines in the drawing.

We claim:

The ornamental design for an electric motor, as shown and described.
